SEALING RING

Nathan Heyman, New York, N. Y., assignor to
 Oscar Heyman & Brothers, Inc., New York,
 N. Y., a corporation of New York

Application August 31, 1939, Serial No. 292,868

4 Claims. (Cl. 63—1)

This invention relates to finger rings, more particularly to sealing rings, and has for its object the provision of an improved ring of this character. The ring of the invention comprises a rotatable member mounted in or attached to an exterior portion of the band of the ring having one or more surfaces upon which letters, names, decorations, symbols, insignia or the like (hereinafter called "characters") are engraved or encrusted. The exterior portion of the rotatable member which contains the character is partly or entirely cylindrical and is constructed and arranged to be rolled over the surface of the wax to impress the character therein. In a particularly advantageous embodiment of the invention the rotatable member is in the form of an elongated cylinder mounted to rotate around its longitudinal axis in suitable supporting brackets attached to the ring band. In view of the relatively long surface which the exterior of the cylinder may provide, various words or names and elaborate designs may be formed on the surface thereof.

The invention will be better understood from a consideration of the accompanying drawing taken in conjunction with the following description, in which:

Fig. 1 is a side elevational view, partly in section, of a ring embodying the invention;

Fig. 2 is an end elevational view of the ring of Fig. 1; and

Figs. 3, 4, and 5 illustrate arrangements of characters such as may be formed on an exterior surface of the rotatable member.

In the accompanying drawing, the ring 1 which may be formed of any suitable metal, such as gold, platinum or the like, has an annular band 2, a recess 3 formed in the upper or head portion of the band, and two upwardly extending brackets 4. A rotatable member 5, preferably in the form of an elongated cylinder, is mounted in the recess between the brackets. Any suitable means may be provided for rotatably mounting and supporting the cylinder in the recess and in engagement with the brackets. As shown in the drawing, each bracket has a pintle 7 arranged to coincide with the central opening 8 in the cylinder. It is understood, of course, that a pin or shaft may be similarly employed.

As best shown in Fig. 2, the median plane 10 of the ring passes through the central portion of the recess and brackets, and the longitudinal axis 11 of the rotatable member 5 is parallel to and preferably embraces the median plane.

Any suitable character 15 may be engraved

in or encrusted upon the cylindrical surface of the rotatable member, such as the characters illustrated in Figs. 3, 4, and 5. In a preferred construction of sealing ring embodying the invention, the rotatable member and means for mounting it in the ring band comprising the recess 3 and brackets 4 are so constructed and arranged that the exterior cylindrical surface of the cylinder 5 projects above the adjacent portions of the ring, thereby enabling the cylinder to contact with and be rolled upon any suitable surface without interference. The ring accordingly provides means for effectively impressing various characters, including names or words, into hot wax or the like by merely pressing the surface of the cylinder against the wax and rolling the cylinder thereover.

I claim:

1. A sealing ring which comprises a finger band, a recess formed in an exterior portion of the band, at least two oppositely disposed brackets, a pintle on each bracket, and a rotatable member mounted on the pintles, said rotatable member having a wax-impressing character formed on the exterior surface thereof and being freely rotatable, whereby the rotatable member may be rolled over wax and the character impressed therein. 20

2. A sealing ring which comprises a finger band, two oppositely disposed brackets on the band, a freely rotatable cylinder mounted between the brackets, a wax-impressing character formed on a surface of the cylinder whereby said cylinder may be rolled over wax and the character impressed therein. 30

3. A sealing ring which comprises a finger band, a cylinder rotatably mounted in an exterior portion of the band, the longitudinal axis of the cylinder being parallel to the median plane of the band, and a wax-impressing character formed on the exterior cylindrical surface of the cylinder, said cylinder being freely rotatable whereby it may be rolled over wax and the character impressed therein. 40

4. A sealing ring which comprises a finger band, a rotatable member having a wax-impressing character formed on a cylindrical surface thereof, means for mounting the rotatable member on the band, said band, mounting means and rotatable member being constructed and arranged that the rotatable member is freely rotatable and may be rolled over wax and the character impressed therein. 45
